Chappell & Earl
ATTORNEYS

UNITED STATES PATENT OFFICE.

LEON GSCHWIND, OF YOUNGSTOWN, OHIO.

CATCH BASIN.

Application filed July 18, 1923. Serial No. 652,366.

To all whom it may concern:

Be it known that I, LEON GSCHWIND, a citizen of the United States, residing at Youngstown, county of Mahoning, State of Ohio, have invented certain new and useful Improvements in Catch Basins, of which the following is a specification.

This invention relates to improvements in catch basins.

10 The main objects of this invention are:

First, to provide an improved catch basin for storm sewers and the like which may be readily adjusted to facilitate connection to the sewer and adjustment to the street grade.

15 Second, to provide an improved catch basin which may be readily cleaned and kept in a sanitary condition.

Third, to provide an improved catch basin for storm sewers having an effective trap 20 which is not likely to become clogged.

Fourth, to provide an improved catch basin in which the parts are formed so that they may be easily manufactured and handled in sections to be set up or assembled at 25 the place of installation.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing, forming a part of this application, in which:

Fig. I is a plan view of my improved 40 catch basin connected to a conduit, the adjustment of the basin to meet conditions of installation being indicated by dotted lines.

Fig. II is a vertical transverse section on a line corresponding to line 2—2 of Figs. I, III and IV.

45 Fig. III is a vertical central section from front to rear on a line corresponding to line 3—3 of Figs. I and II.

Fig. IV is a rear perspective view of the 50 bottom section of the basin with certain removable parts mounted therein.

Fig. V is a detail vertical section on a line corresponding to line 5—5 of Fig. II, showing details of the cover mounting, the cover being shown in open position by dotted lines 55 and in closed position by full lines.

In the drawing similar reference characters refer to similar parts throughout the several views, and the sectional views are taken looking in the direction of the little arrows at the ends of the section lines. 60

Referring to the drawing, my improved catch basin, in the embodiment illustrated, comprises a bottom section 1, an intermediate section 2 and a top section 3. The bottom section 1 is preferably cylindrical as illustrated and is provided with a transversely disposed channel-like trap passage 5. This extension 4 extends across the bottom of section 1 and at the rear and at the front thereof—see Figs. III and IV. 70

The bottom section is provided with an inwardly facing joint shoulder 6 receiving the coacting shoulder 7 of the intermediate section 2 which is cylindrical to correspond to the body portion of the bottom. The sections 1 and 2 are provided with opposed ears 8 and 9 respectively adapted to receive the coupling bolts 10. 75

The intermediate section is provided with an extension 11 at the rear complementing 80 the rear end of the extension 4 of the bottom section and providing a trap inlet opening. The intermediate section 2 is also provided with a front extension 12 complementing the front end 13 of the extension 4 providing a discharge connection for the basin to which the sewer pipe or conduit 14 may be connected. These parts are also provided with the coacting ears 8 and 9. 85

The intermediate section has an inwardly projecting flange 15 at its upper edge provided with an upwardly facing groove 16. The top section 3 has a cylindrical bottom portion fitting in this groove so that the top may be rotatively adjusted to properly position its curb inlet opening 17 or, in other words, to permit the positioning of the basin so as to bring its discharge in proper relation to the sewer or conduit 14 permitting a direct connection or obviating elbows in 100 the conduit. 90

The top section is preferably secured by means of the coupling lugs 18 engaging under the flange 16, the top section being provided with ears 19 to receive the clamping bolts 20 by means of which the lugs are clamped against the underside of the flange. 105

To further facilitate adjustment the curb grate 21 is supported by a frame 22 which has end and front walls constituting ex- 110

tensions for the walls of the top section, the end walls being provided with slots 23 for the bolts 24 so that the member 22 is adjustably secured in position. This is of advantage in the original setting of the basin and also, in the event of paving or re-surfacing the street or settling of the basin or the line, adjustment may be made as conditions require.

10 The top section is provided with a cover 25 having hinge lugs 26 engaging holes 27 in the hinge plates 28 secured on the inner side of the top section—see Figs. III and V. This permits the removal of the cover when 15 desired.

To facilitate cleaning the trap, the trap passage is provided with a removable cover plate 29 resting in the shoulders 30—see Fig. II. At the front end of this plate is a removable passage wall plate 31 secured by the removable bolts 32 and having lugs 34 overlapping the front end of the plate 29. The trap inlet grate 35 is provided with lugs 36 overlapping the rear end of this 25 plate and is removably secured in position by the bolt 37 passed through lugs 38 on the top section and the lug 39 on the intermediate section. This lug 38 can only be utilized when the top section is positioned 30 as shown in full lines in the drawing. When the top section is otherwise adjusted, the lug 38 is swung out of alignment.

My improved catch basin is easily kept in a sanitary condition, is very easily installed and may be adjusted, as stated, to meet a changed condition of the curb level such as is occasioned by re-surfacing the street.

I have illustrated and described an embodiment which I have found very practical. I have not attempted to illustrate or describe other modifications or adaptations as I believe the disclosure made will enable those skilled in the art to which my invention relates to embody or adapt the same as may be desired.

Having thus described my invention, what I claim as new and desire to secure by Letters Patent, is:

50 1. In a catch basin, the combination of a bottom section provided with a channel-like trap passage extension disposed transversely thereof, an intermediate section provided with an extension at its rear side complementing the rear end of said trap passage extension providing a trap inlet and an extension at its front side complementing the front end of said trap passage extension providing a trap discharge, said intermediate section being cylindrical at the top, a removable cover for said trap passage, a removable passage wall plate disposed at the front end of said cover plate, a removable grate for the trap inlet, said wall plate 55 and grate having lugs overlapping the ends 60 65

of said cover plate whereby it is secured in position, a top section having a cylindrical bottom fitting the cylindrical top portion of said intermediate section whereby it may be rotatably adjusted thereon, means for securing said top section in its adjusted positions on said intermediate section, said top section being provided with a curb inlet opening, and a curb grate frame comprising a front and end walls vertically adjustable within said curb inlet opening thereby facilitating grade adjustment. 75

2. In a catch basin, the combination of a bottom section provided with a channel-like trap passage extension disposed transversely thereof, an intermediate section provided with an extension at its rear side complementing the rear end of said trap passage extension providing a trap inlet and an extension at its front side complementing the front end of said trap passage extension providing a trap discharge, said intermediate section being cylindrical at the top, a removable cover for said trap passage, a removable passage wall plate disposed at the front end of said cover plate, a removable grate for the trap inlet, said wall plate and grate having lugs overlapping the ends of said cover plate whereby it is secured in position, and a top section provided with a curb inlet opening. 90 95

3. In a catch basin, the combination of a bottom section provided with a channel-like trap passage extension disposed transversely thereof, an intermediate section provided with an extension at its rear side complementing the rear end of said trap passage extension providing a trap inlet and an extension of its front side complementing the front end of said trap passage extension providing a trap discharge, said intermediate section being cylindrical at the top, a removable cover for said trap passage, a removable passage wall plate disposed at the front end of said cover plate, a removable grate for the trap inlet, a top section provided with a cover and with a curb inlet opening, said top section having a cylindrical bottom fitting the cylindrical top of said intermediate section whereby it may be rotatably adjusted thereon, and a curb grate frame comprising a front and end walls vertically adjustable within said curb inlet opening thereby facilitating grade adjustment. 100 105

4. In a catch basin, the combination of a bottom section provided with a channel-like trap passage extension disposed transversely thereof, an intermediate section provided with an extension at its rear side complementing the rear end of said trap passage extension providing a trap inlet and an extension of its front side complementing the front end of said trap passage extension providing a trap discharge, said intermediate section being cylindrical at the top, a removable cover for said trap passage, a removable passage wall plate disposed at the front end of said cover plate, a removable grate for the trap inlet, said wall plate and grate having lugs overlapping the ends 115 120 125 130

said trap passage, a removable grate for said trap inlet, and a top section provided with a cover and with a curb inlet opening, said top section having a cylindrical bottom 5 fitting the cylindrical top of said intermediate section whereby it may be rotatably adjusted thereon.

5. In a catch basin, the combination of a bottom section provided with a channel- 10 like trap passage extension disposed transversely thereof, an intermediate section provided with an extension at its rear side complementing the rear end of said passage extension providing a trap inlet and an extension 15 of its front side complementing the front end of said passage extension providing a trap discharge, a removable cover for said trap passage, a removable passage wall plate disposed at the front end of said cover 20 plate, a removable grate for said trap inlet, said wall plate and grate having lugs overlapping the ends of said cover plate whereby it is secured in position, and a top section provided with a cover and with a curb inlet 25 opening.

6. A catch basin comprising a top sec-

tion mounted for rotatable adjustment and provided with a cover and with a curb inlet opening, a curb grate, and a supporting frame therefor comprising a front, end wall, 30 vertically adjustable within said curb opening thereby facilitating grade adjustment.

7. A catch basin comprising a body portion provided with a discharge, a top having a curb inlet opening at one side thereof, 35 said body and top having cylindrical coacting joint members whereby the top may be rotatably adjusted relative to the body portion, and a curb member mounted for vertical adjustment within said curb inlet opening, its walls constituting extensions for the walls of the basin thereby facilitating grade adjustment.

8. A catch basin provided with a curb inlet, a wall member vertically adjustable 40 within said inlet to facilitate curb adjustment, and a grate mounted on said adjustable wall member.

In witness whereof, I have hereunto set my hand and seal.

LEON GSCHWIND. [L.S.]
